UNITED STATES PATENT OFFICE

HORACE D. STEVENS, OF AKRON, OHIO, ASSIGNOR TO THE FIRESTONE TIRE AND RUBBER COMPANY, OF AKRON, OHIO, A CORPORATION OF OHIO

MACHINE FOR COATING AIR BAGS

Application filed January 14, 1927. Serial No. 161,050.

This invention relates to machines for coating air bags or other annular objects.

The purpose of the invention is to provide a machine for applying a coating of liquid to the surfaces of an article of torus shape and particularly for applying on air bags used in the manufacture of pneumatic tires, a thin uniform coating of "dope" or emulsion of glycerine and soapstone, mica, talc, etc., preparatory to placing the bag in an unvulcanized tire casing, to prevent the bag from adhering to the casing during vulcanization of the latter.

One object of the invention is to provide an annular series of revolving brushes or wipers for engaging the sides and outer periphery of an annular or torus-shaped article. A further object is to provide means for guiding and revolving said article about its axis to present its entire annular surface to said brushes. Another object is to provide a revolving disc or paddle partly submerged in a liquid supply container and partly contacting the revolving brushes for transferring a small amount of liquid from the container to the brushes. Still another object is to provide means for adjusting the quantity of the liquid transferred by the revolving disc.

The foregoing and other objects are obtained by the device illustrated in the accompanying drawings and described below. It is to be understood that the device is not limited to the specific form thereof disclosed herein.

Of the accompanying drawings:

Figure 1 is a front elevation, partly in section, of a machine embodying the principles of the invention; and

Figure 2 is a left end elevation thereof, partly broken away.

Referring more particularly to the drawings, 10 represents the frame having journaled therein upper and lower shafts 11 and 12 respectively. The upper shaft has

attached thereto a pair of spaced discs 13, 13 having mounted on the confronting inner faces thereof a plurality of brushes or wipers 14, 14 positioned with their long dimension radially of the disc and with their free ends directed toward each other. A sleeve 15 fixed on shaft 11 also carries a series of brushes or wipers 16, 16 mounted radially thereof and spaced between the brushes or wipers 14, the free ends of brushes or wipers 16 being directed radially outward. Rotation of shaft 11 is accomplished by means of a motor 17 driving a chain 18 trained over a sprocket 19 fixed to shaft 11.

Shaft 12 has fixed thereto a pair of spaced discs 20, 20 having radially mounted therebetween a series of plates 21. The lower portions of the discs 20 and plates 21 are submerged in a liquid 22 contained in a receptacle 23 mounted on frame 10, while the upper portions contact with brushes or wipers 14 and 16 to transfer liquid thereto from the receptacle as shafts 11 and 12 are rotated. Shaft 12 is rotated at a slower rate of speed than shaft 11 by means of chain 24 trained over small sprocket 25 fixed on shaft 11 and large sprocket 26 fixed on shaft 12. Means for rotating the annular or torus-shaped article 27 (indicated by dotted lines) during the coating operation, is provided by rollers 28, 28 mounted on frame 10 and driven by a chain 29 meshing with sprockets 30, 30 fixed to said rollers and trained over adjusting idlers 31, 31 and drive sprocket 32 fixed on shaft 11. Vertical arms 33, 33 attached to frame 10 carry shafts 34, 34 upon which are mounted rollers 35, 35 for the purpose of guiding the annular object 27 and holding the same in proper vertical alignment. Receptacle 23 is provided with flaring side extensions 36, 36 to catch any liquid which may be splashed by the brushes, and adjustable scraper 37 may be suitably mounted adjacent discs 20 to permit any desired thickness of liquid to remain thereon. The quan-

5 tity of liquid transferred to the brushes is thus variable for obtaining the utmost efficiency in the coating operation. As many of the above described units as desired may be mounted on one frame and operated by a single drive means, the present drawings showing two units mounted in the frame.

10 The operation of the machine has been set out in connection with the description of the structure thereof and need not further be explained. If desired, plates 21 and central brushes or wipers 16 may be omitted and the side brushes 14 alone employed to perform the coating operation, or if a thick coating 15 of liquid on the article is desired, shaft 12 and discs 20, 20 may also be omitted and the brushes 14 allowed to dip directly into fluid receptacle 23. Other modifications of the invention may be resorted to without departing from the spirit thereof or the scope of the appended claims.

20 What is claimed is:

25 1. A machine for coating annular objects, comprising a frame having journaled therein upper and lower shafts, a pair of spaced discs fixed to said upper shaft, a series of wipers mounted radially about said discs on the confronting faces thereof for engaging the sides of an annular article to be coated, a central series of wipers mounted radially 30 about said upper shaft and affixed thereto between said discs for engaging the periphery of the annular article to be coated, a pair of spaced discs fixed to said lower shaft and having a series of radial plates mounted therebetween, the upper portions of 35 the last-named discs and said plates engaging a portion of the side engaging wipers and central wipers respectively, a receptacle for containing liquid in which said last 40 named discs and plates are adapted to be partly submerged, whereby rotation of said discs and said wipers will transfer a quantity of liquid from the receptacle to the sides 45 and periphery of the annular article to be coated, means for varying the quantity of liquid thus transferred, driven rollers for supporting and circumferentially rotating the annular object to be coated, means for 50 guiding the latter on said rollers, and means for rotating said shafts and said rollers.

55 2. A machine for coating annular objects, comprising a frame having journaled therein upper and lower shafts, a pair of spaced discs fixed to said upper shaft, a series of wipers mounted radially about said discs on the confronting faces thereof for engaging the sides of an annular article to be coated, a central series of wipers mounted radially 60 about said upper shaft and affixed thereto between said discs for engaging the periphery of the annular article to be coated, a pair of spaced discs fixed to said lower shaft and having a series of radial plates mounted therebetween, the upper portions of 65

70 the last-named discs and said plates engaging a portion of the side engaging wipers and central wipers respectively, a receptacle for containing liquid in which said last 75 named discs and plates are adapted to be partly submerged whereby rotation of said discs and said wipers will transfer a quantity of liquid from the receptacle to the sides and periphery of the annular article to be coated, and means for rotating said shafts.
